UNITED STATES PATENT OFFICE.

ARTHUR T. TIMEWELL, OF SPOKANE, WASHINGTON, ASSIGNOR TO ALBERT DICKINSON, OF CHICAGO, ILLINOIS.

SACK FILLING AND SEWING MACHINE.

SPECIFICATION forming part of Letters Patent No. 539,455, dated May 21, 1895.

Application filed September 26, 1894. Serial No. 524,164. (No model.)

To all whom it may concern:

Be it known that I, ARTHUR T. TIMEWELL, a citizen of the United States, residing in Spokane, in the county of Spokane and State 5 of Washington, have invented a new and useful Improvement in Sack Filling and Sewing Machines, of which the following is a specification.

My invention relates to apparatus for filling sacks or bags with grain or other material, and closing or sewing the mouths of the sacks or bags after they have been filled.

The object of my invention is to provide an automatic machine or apparatus of a simple 15 and efficient construction, by means of which sacks or bags may be rapidly, conveniently and evenly filled, each with a fixed or measured amount of material, the mouths of the sacks or bags securely sewed, and the filled 20 and sewed sacks or bags discharged from the machine; and, to this end my invention consists, primarily, in the combination with a filling and weight or bulk measuring mechanism for delivering the requisite quantity of 25 grain or other material into each sack, of an opening and closing movable or traveling sack holder for holding the sack open while being filled, closing the same and holding it closed while being carried past the sewing mechanism 30 and sewed, a sewing mechanism fixed on the frame of the machine, and a conveyer mechanism for supporting and conveying the filled sack from the filling position past the sewing mechanism and discharging the filled 35 and sewed sack from the machine.

It also consists, in connection with a stationary sack filling device and a stationary sewing device or mechanism, of a series of two or more similar movable or traveling and 40 opening and closing sack holders to enable one sack to be filled and another sewed and discharged at the same time, thus greatly increasing the capacity of the machine.

It also consists, in connection with the filling 45 device and stationary sewing mechanism, of a sack holder and a track or way along which the sack holder travels on the machine, and the carrier for supporting and conveying the filled sack in an upright position under and 50 past the sewing mechanism, of yielding or spring supports for said carrier, so that the

yielding of the carrier may compensate for any variation or inaccuracy in the action of the co-operative filling mechanism. By combining with the stationary sewing mechanism 55 and sack conveyer a filling mechanism which operates to deliver an approximately measured quantity to each bag, I, in a great measure, prevent any considerable variation in the height or length of the filled bag and the 60 consequent weight or strain of the filled bag or its holder against the sewing mechanism or its supports; but to further perfect the machine and guard against danger of injury to or stopping of the mechanism by the attempt 65 to pass through the machine filled bags of undue height or length, I mount the bag carrier, or that portion of it which conveys the bag under the sewing mechanism, on springs or yielding supports, so that the distance or 70 space between the carrier and the table or frame upon which the sewing mechanism is mounted and along which the bag holder travels, may automatically accommodate itself to the length or height of the filled bag. 75

My invention further consists, in connection with the bag filling mechanism and opening and closing traveling bag holder, of the track or way along which the bag holder travels, and a device or mechanism for moving 80 said bag holder along said track or way into engagement with which the bag holder is thrown by the act of closing the same.

It further consists, in connection with the filling mechanism, sewing mechanism, and 85 traveling bag holder, of a device for automatically cutting the thread and holding the severed end of the thread.

It also consists, in connection with the filling mechanism and sewing mechanism and 90 series of bag holders, of a track or way along which the bag holders travel from the filling position past the sewing mechanism to the discharging position, said track or way for the holders having an open mouth at the discharge 95 end of the machine so that no injury can result to the mechanism by one holder following another successively.

It further consists, in connection with the bag filling mechanism and sewing mechanism, 100 of an open and closing traveling sack holder furnished with movable or withdrawable

hooks or teeth for engaging the mouth of the sack to facilitate the automatic discharge or disengagement of the sack from the holder after the sack has been sewed.

5 It further consists in the novel construction and combinations of parts and devices herein shown and described, and specified in the claims.

The filling and measuring mechanism, 10 which operates to fill each sack to a fixed or measured extent, coacts directly with the holder to enable it to properly close the sack, which it could not do without danger of breakage if the sack were accidentally filled too full; 15 also directly with the sewing mechanism and especially with the needle and looper thereof, which cannot properly operate if the sack is filled too full; and also with the sack conveyer and track for the holder between which the 20 sack must pass, and between which it cannot pass properly if filled much too full. The combination of a measuring sack filler with the other parts it will thus be seen is necessary or important for the proper and successful 25 operation of the other principal parts; and the mutual coactive relation and co-operation of the several parts are close and interdependent upon the several parts. In this connection it should also be observed that by combining 30 a series of holders with the other principal parts, each of the holders co-operating in turn with each of the other principal parts, and the other principal parts being at the same time so arranged and combined as to permit the several holders to co-operate simultaneously therewith, the capacity of the machine as a whole is many times increased, one bag thus being filled while another is being sewed and still another being discharged from 35 the machine.

In the accompanying drawings, which form a part of this specification, I have illustrated at Figures 1 and 1^a, in side elevation, a machine embodying my invention. Fig. 2 is a 40 plan view somewhat enlarged. Fig. 3 is a partial vertical section taken on line 3 3 of Fig. 1. Fig. 4 is an enlarged detail vertical cross-section through the sewing mechanism on line 4 4 of Fig. 2. Fig. 5 is an enlarged detail 45 plan view of the sewing mechanism. Fig. 6 is an enlarged plan view, partly in section, of one member of the thread cutter and holder. Fig. 7 is an enlarged detail plan view of the 50 sack-holder, showing the same open. Fig. 8 is a similar view showing the same closed. Fig. 9 is an enlarged cross-section on the line 55 9 9 of Fig. 8. Fig. 10 is a detail view illustrating the means or arrangement by which the closing of the bag-holder operates to throw 60 it into engagement with the gear mechanism for propelling it along its track or way. Figs. 11 and 12 are enlarged detail views of parts hereinafter to be described.

In the drawings the same parts, appearing 65 in different figures, are indicated by the same letters of reference.

In the drawings A represents the frame; B,

the filling and measuring device; C, the sewing device or mechanism; D, the movable opening and closing bag holder; F, the slotted 70 track or way along which the bag holder is moved.

G and H are carriers for supporting and conveying the bag past the sewing mechanism from the filling position to the discharging 75 position, and K the thread cutting and holding device.

The bag filling and measuring device B is preferably one adapted to measure by bulk instead of by weight, and comprises preferably a measuring chamber or hopper B' of a capacity corresponding to that of the bag, a discharge spout B², a delivery spout B³ and two valves B⁴ B⁵, and an operating lever B⁶, the upper valve and lever being long enough 85 and arranged so that the upper valve is completely closed before the lower one begins to open. By this means a definite quantity of material is filled into each bag X.

The sewing device or mechanism C has a 90 frame C' upon which the needle, looper and other parts are mounted; and which frame C' is fixed by suitable screws or bolts c to the frame A, or the top piece or table A' of said frame A. The bolts c extend through only 95 one end of the sewing machine frame C', thus leaving the other end of said frame C' free; so that the needle C² and looper C³, and other co-operative parts of the sewing mechanism may not be affected or thrown out of proper engagement with, or relation to, each other by any vibrations of the frame A or its table A', as might be the case if the sewing machine frame C' were supported or attached to the table A' at both sides of the slotted track 100 or way F.

The frame plate A' has an opening A² to receive the sewing device C, as is clearly illustrated in Figs. 4 and 5, so that the needle C² may reciprocate in said opening just below 110 the upper surface of the table or plate A' and across the slot f of the slotted way F, along which the bag holders D travel or move, so that the line of stitching is made just beneath the lower edge or surface of the bag holder. 115 The sewing machine frame C' is arched over the slotted way F to give room for the bag holders to pass between the same and the track F on the frame plate A'.

The sewing mechanism may be of any suitable form or kind known to those skilled in the art. That however which I prefer to use in practicing my invention is illustrated in the drawings, and comprises a reciprocating needle C², a continuously revolving looper C³, a presser foot C⁴, and suitable means for reciprocating the needle and revolving the looper, consisting preferably of an upright shaft C⁷ carrying a gear C⁵ provided with a crank pin C⁶, a pitman C⁷, connected at one end to said crank pin and at the other end to a crank arm C⁸ on a crank shaft C⁹, the other arm, C¹⁰ of which is connected by a pivoted link C¹¹ with the needle bar C¹². The same

upright shaft C¹³ is provided with a gear C¹³ meshing with an intermediate gear C¹⁴ that meshes with a gear C¹⁵ on the shaft C¹⁶ of the looper.

5 The series of bag holders D, two or more in number, so that the bag in one may be filled while that in another is being sewed and discharged, each consists, preferably, of four bars D', D', D', D', hinged together at their ends by pivots D² so that they may be opened to assume a diamond-shape, as illustrated in Fig. 7, or closed together in a straight line, as illustrated in Fig. 8. A spring D³ coiled around one of the pivots D² serves to throw 15 or hold open the holder normally. The holder D, or each of its hinged bars D', is provided with a series of movable or withdrawable hooks or pointed pins or devices d to engage the mouth edge of the sack. These movable 20 or withdrawable hooks d on which the sack is hung, are preferably fixed to rock shafts d', one on each bar D', by rocking or rotating which the hooks may be withdrawn or moved from engagement with the sack in order to 25 discharge the sack from the holder. The hooks d or the rock shafts d' are preferably held in their normal position—that for their withdrawal from the sack—by springs d², preferably coiled around the rock shafts and the 30 rock shafts d' are preferably rotated or rocked to throw the hooks into position for hanging the sack thereon automatically by the act of opening the holder to receive the sack. This automatic movement of the hooks from 35 their sack discharging or withdrawing position to their sack hanging or receiving position may be accomplished by any suitable means or mechanism. A simple and convenient means for accomplishing this purpose is 40 illustrated in the drawings, and consists in providing each of the hook bearing rock shafts d' with a curved or cam-shaped arm d³ that engages projections d⁴ on the pivoted bars D', as is clearly illustrated in Fig. 9, taken 45 in connection with Figs. 7 and 8. The projection or part d⁴ on the bar D' that is engaged by the opposite curved arm d³ is, as illustrated in the drawings, also the bearing or housing for the rock shaft d'. By this 50 means, as the contiguous pivoted bars D' D' are thrown open or separated, the curved arm d³, engaging the projection d⁴, inclines the hooks d upward into position for conveniently receiving and hanging the sack thereon. As, 55 or when, the bars D' D' are closed the curvature or cam-shape of the arm d³ permits the springs d² to throw the hooks d into a horizontal position, so that the further lateral opening or separation of the bars D' D' with- 60 draws the hooks d from the sewed seam of the filled sack. This will be readily understood from Figs. 9, 7, 8 and 2.

The track or way F on the top plate A' of the frame A is provided with a longitudinal slot f to receive or accommodate the seam or the closed mouth edges of the bag. This slot f is enlarged at the filling station into a dia-

mond-shaped opening f' to receive and accommodate the open mouth of the bag at the time it is being filled. The track or way F for the holders D has an enlargement F' at the filling station to receive or accommodate the holder in its open form, and another enlargement F² at the discharge end of the machine to permit the holder to open and the filled and sewed sack to be released from the holder; that is to say, the two side walls f² f² of the track between which the holders pass, conform to the closed form of the holder at that part of the track where the holders are being carried past the sewing mechanism, so that these side walls will serve to keep the holder closed as well as to properly guide the same along; and these side walls f² f² diverge at the filling station F' to give room for the holder when it is open; and these side walls f² f², again diverge at the discharge point F² to permit the bars D' of the holder to open to discharge the filled and sewed sack. The track F at the filling station has a closed end or abutment F³ against which the rear end of the holder D abuts, so that the act of closing the open holder will serve to project the front end of the holder forward and thus throw the holder into engagement with the mechanism for propelling the holder along the track F. This is clearly illustrated in Fig. 10 in connection with Fig. 2. The track F has an open end or mouth F⁴ at its discharge end, so that one holder following another may not be obstructed or stopped by the holder ahead of it, as might be the case if the track F had an abutment or closed end at the discharge end of the machine.

The means for supporting and conveying the sack from the filling station past the sewing mechanism to the discharge position, consists preferably of two movable carriers G and H, in order to permit the bag to be conveniently shaken or vibrated up and down at the time it is being filled. Both these carriers are preferably of the endless belt type. To shake or vibrate the bag up and down at the time it is being filled, the carrier G which supports the bag at this time and serves to move it onto the other carrier H, is mounted on an up and down movable or vibrating frame G', and to enable this carrier G and its frame to vibrate up and down conveniently, I furnish the same with a counter-balance G², the counter-balance being preferably in the form of a coiled spring, connected at one end to the main frame of the machine and at the other to the vibrating frame G', the connection to the vibrating frame G' being preferably made through the mechanism which supports and operates or vibrates the frame G'. The frame G' is supported and vibrated by the crank arm or lever G⁴ on the shaft G⁵ of the pulley or wheel G⁶, in connection with the rope or chain G⁷, attached at its two ends to the frame G' passing over or around the pulleys or sprocket wheels G⁶, G⁸. The chain G⁷ is secured at an intermediate part of its length to

the periphery of the pulley G^6 , one strand of the chain passing directly down to one side of the frame G' , and the other strand of the chain passing over the pulley G^8 and thence down to the other side of such frame G' , so that both sides of the frame may be raised and lowered evenly and simultaneously from the crank G^4 . At the opposite end of the frame G' a similar chain G^7 , as indicated in Fig. 3, is similarly arranged, so that the frame G' is thus supported at each of its four corners by the chains G^7 .

The carrier G travels on pulleys or sprocket wheels G^{13} , G^{14} on shafts G^{15} , G^{16} journaled on the frame G' , and the same is intermittently operated—that is to say, the carrier G remains stationary while the bag is being filled and is then set to moving or revolving in order to convey the filled bag onto the carrier H , which preferably moves continuously.

The carrier H travels on pulleys or sprocket wheels H' , the shafts H^2 of which are journaled on the frame H^3 , which is provided with yielding or spring supports H^4 , so that the frame H may yield or give when necessary, to give room for an abnormally high or long bag between itself and the top plate A' of the frame or the bag holder track or guide F , mounted thereon. This insures against danger of stoppage, breakage or injury arising from the irregular length or height of the filled bags, and is a matter of importance and value in the practical operation of the machine, as I have found by my experiments.

The thread cutting and holding device or mechanism K , consists preferably of two sliding spring actuated bars k , mounted on the frame plate A' of the machine, and each provided with a pin or roller k' projecting in the path of the holders D in the track F , and each furnished with a knife or cutter k^2 and thread holding jaw k^3 , so that the instant the holder D passes the projection k' the sliding bars k k , carrying the knives and thread holding jaws, will be actuated or closed against each other by their springs k^4 and thus sever the thread and hold the free end of the same. When the next holder advances into position for the bag therein to be sewed, the thread cutting and holding sliding bars k k are automatically retracted into position for the succeeding operation.

Any suitable means or mechanism may be employed for closing the open holder D at the filling position after the sack is filled. That which I prefer is illustrated in the drawings, and consists of a pair of sliding bars M , M , mounted on the frame of the machine in suitable guides M' , furnished with anti-friction rollers m m , adapted to engage the holder bars D' D' , and actuated by bell crank levers M^2 M^2 , connected by rods M^3 M^3 with the levers M^4 M^4 , which are pivoted together at m' and to the frame at m^2 m^2 , and one of which is furnished with a treadle M^6 , so that the two slides M M are similarly and simultaneously operated.

Any suitable means may be employed for propelling or moving the holders D along the track or way F from the filling position past the sewing mechanism to the discharging position. The means which I prefer to employ consists in the gears N N , mounted above the track F , one on each side of the sewing mechanism, and which engage rack N' secured to the holders D . The act of closing the holder pushes the same forward and throws its rack N' into engagement with the first gear N , as the holder is elongated by the act of closing the same. The gears N are secured to shafts N^2 having gears N^3 which mesh with gears N^4 on shafts N^5 , carrying gears N^6 that mesh with the gear N^7 on the driving shaft P^2 .

The sewing machine may likewise be operated in any suitable manner, but preferably by a bevel gear P engaging the bevel gear C^5 , the bevel gear P being secured to a sleeve P' which is thrown into gear with the driving shaft P^2 by a sliding clutch p , which is operated automatically by an arm or lever p' projecting into the track F in the path of the bag holder D . A spring p^2 serves to retract the clutch and throw the sewing machine out of gear when the sewing of the bag is completed and the bag holder D is carried past said clutch operating arm p' .

The carrier G and the carrier H may both be conveniently driven by a single sprocket chain T , engaging a sprocket wheel T' on the shaft N^2 , and extending over or around the sprocket wheels T^2 T^3 of the carriers G and H , and over or around the idlers T^4 , T^5 and T^6 . The sprocket wheel T^2 on the vibrating carrier platform G' is thrown into engagement with the driving shaft of the carrier G by a sliding clutch g , having a pin g' which fits in a stationary cam groove g^2 attached to the frame of the machine, so that when the frame G' is raised up to its full limit to bring the carriers G and H about on a level, the intermittently operating carrier G will be thrown into operation.

The operation of the machine is as follows: The bulk or weight measured quantity of material necessary to fill a sack being in the measuring chamber B' of the filling mechanism B , and an open sack holder with sack attached being in position on the track F at the filling position F' , the operator opens the lower valve of the measuring chamber or hopper and fills the sack, at the same time shaking the sack up and down if necessary by operating the vibrating carrier platform G' with the lever G^4 . After the sack has thus been filled with a definite and measured quantity of material, the operator with crank G^4 lifts the carrier frame G' , and thus through the action of the clutch g sets the carrier G in motion; and the operator, momentarily after this, with his foot on the treadle M^6 operates the sliding bars M and closes the bag holder D , and thus simultaneously throws the bag holder into engagement with its propelling mechanism or gear N . The closed bag holder

and bag are then conveyed, the former along the track F and the latter on the carriers G and H past the sewing mechanism C, which is automatically set in operation by the movement of the holder D along the track F, as before described. After the sewing is completed and the bag holder passes beyond the spring actuated thread cutting and holding device, the two opening and closing parts of this device automatically close and sever the thread from the bag, and at the same time grasp the free end of the thread. The bag holder continuing its movement along the track F, after passing the point where the side walls f^2 f^2 of the track diverge is then automatically thrown open by the spring D³ at one of the pivots of the holder; and as the bars D'D' of the holder open or separate, the hooks or pins d are withdrawn from the sack; and the further movement of the carrier H discharges the sack from the machine. In the meantime another holder of the series has been placed in the machine at the filling position and filled in the same manner, so that the operation is successively continuous.

The springs supports H' for the carrier frame H' are attached to the frame A through adjusting screws H⁵ so that the height of the carrier H may be adjusted for operation upon bags of different sizes or lengths.

The bars D' of the holder D are preferably provided with serrations d⁶ on their meeting edges.

I claim—

35 1. The combination with a bag filling and measuring device, of an opening and closing movable or traveling sack holder, a track or way along which such holder moves, a carrier for conveying the sack along, and a stationary sewing device or mechanism for sewing the mouth of the sack as it is conveyed along, substantially as specified.

45 2. The combination with a sack filling and measuring device, of an opening and closing movable sack holder, and a stationary sewing mechanism, substantially as specified.

50 3. The combination with a sack filling and measuring device, of a movable sack holder, a sack carrier, and a stationary sewing device or mechanism, substantially as specified.

55 4. The combination with a sack filling device, of a series of movable sack holders and a sewing device or mechanism, substantially as specified.

60 5. The combination with a sack filling device, of a series of movable sack holders, a slotted track or way along which said holders travel and a stationary sewing device, substantially as specified.

65 6. In a sack filling and sewing machine, the combination with a sack filling device, of a movable sack holder, a track or way for said holder, a sewing device and a thread cutting device, substantially as specified.

70 7. In a sack filling and sewing machine, the combination with a sack filling device, of a movable sack holder, a track or way for said

holder, a sewing device, and a thread cutting and holding device, substantially as specified.

8. In a sack filling and sewing machine, the combination with a sack filling device, of a movable sack holder, a track or way for said holder, a sewing device, and a thread cutting and holding device comprising two opening and closing spring actuated sliding bars, furnished with a projection in the path of the sack holder, substantially as specified.

9. In a sack filling and sewing machine, the combination with a sack filling device, of a movable sack holder, a track or way for said holder, a sewing device, a sack carrier mounted on a frame provided with spring or yielding support to admit sacks of varying lengths or heights to pass between said track and said carrier, substantially as specified.

10. The combination with a sack filling device, of an opening and closing movable sack holder, a track or way for the holder, mechanism for propelling the holder along said track, and means for closing the sack holder, the whole being combined, adapted and arranged to cause the closing of the sack holder to throw it into engagement with said sack holder propelling mechanism, substantially as specified.

11. The combination with a sack filling device, of an opening and closing movable sack holder, a track or way for the holder, mechanism for propelling the holder along said track, and means for closing the sack holder, the whole being combined, adapted and arranged to cause the closing of the sack holder to throw it into engagement with said sack holder propelling mechanism, said track or way having a closed end or abutment at the filling position end thereof for the rear end of the sack holder to abut against as it is being closed, substantially as specified.

12. The combination with a sack filling device, of a series of movable sack holders, a track or way for said holders, and a sewing device, said track or way having an open mouth at its discharge end to prevent one holder therein from obstructing the movement of a succeeding holder, substantially as specified.

13. The combination with a sack filling device, of a movable sack holder, a slotted track or way for said holder, and a sewing device having a frame secured at one of its ends only to the frame of the machine at one side of said slotted track to prevent vibrations of the machine from interfering with the operation of the sewing mechanism, substantially as specified.

14. The combination with a sack filling and measuring device, of a movable sack holder furnished with movable or withdrawable devices for engaging the mouth of the sack, a track or way for the holder, and a sewing device, substantially as specified.

15. The combination with a sack filling and measuring device, of a sack conveyer and a sack sewing mechanism, substantially as specified.

16. The combination with a sack filling and

- measuring device, of a series of movable sack holders, a track or way for the holders, a sack sewing mechanism and a sack conveyer, substantially as specified.
17. The combination with a sack filling and measuring device, of a series of movable sack holders, a track or way for the holders, a stationary sewing mechanism, an up and down movable or vibrating sack carrier for supporting the sack at the filling station and moving it therefrom, substantially as specified.
18. The combination with a sack filling and measuring device, of a series of movable sack holders, a track or way for the holders, a stationary sewing mechanism, an up and down movable or vibrating sack carrier for supporting the sack at the filling station and moving it therefrom, and a second sack carrier for conveying the sack past the sewing mechanism and discharging the same from the machine, substantially as specified.
19. The combination with a sack filling and measuring device, of a series of movable sack holders, a track or way for the holders, a stationary sewing mechanism, an up and down movable or vibrating sack carrier for supporting the sack at the filling station and moving it therefrom, and a second sack carrier for conveying the sack past the sewing mechanism and discharging the same from the machine, said second mentioned sack carrier being provided with a yielding or spring support, substantially as specified.
20. The combination with a sack filling device, of an opening and closing movable sack holder furnished with movable devices for engaging the mouth of the sack, a track or way for the holder, a sewing device, and means for operating said movable sack holding devices on the holder by the opening and closing of the holder, substantially as specified.
21. The combination with a sack filling device, of a movable sack holder, a track or way for the holder, a sewing device provided with a clutch operating arm projecting in said track or way in the path of said holder, so that the movement of said holder along said track will serve to throw said sewing device in and out of gear, substantially as specified.
22. The combination with a sack filling device, of an opening and closing spring actuated sack holder, a track or way for said holder provided with side walls for holding said sack holder closed during the sewing operation, and a sewing device, substantially as specified.
23. The combination with a sack filling device, of an opening and closing spring actuated sack holder, a track or way for said holder provided with side walls for holding said sack holder closed during the sewing operation, and a sewing device, the side walls of said track or way diverging at the discharge end of the machine to permit the spring actuated holder to be automatically opened by its spring, substantially as specified.
24. The combination with a sack filling device, of an opening and closing spring actuated sack holder, a track or way for said holder provided with side walls for holding said sack holder closed during the sewing operation, and a sewing device, the side walls of said track or way diverging at the discharge end of the machine to permit the spring actuated holder to be automatically opened by its spring, substantially as specified.
25. The combination with an opening and closing sack holder furnished with a rack, of a track or way therefor, a sack sewing mechanism, and revolving gears engaging said rack for propelling the sack holder along said track, said track having side walls to hold the holder closed, said side walls diverging at the discharge end of the machine to permit the holder to open, substantially as specified.
26. The combination with a sack filling and measuring mechanism, of an opening and closing sack holder for holding the sack open while being filled and closed while being sewed, a sack sewing device, and mechanism for closing said holder, said sack closing mechanism, a pair of oppositely moving sliding bars, levers $M^2 M^2$, levers $M^4 M^5$ pivoted together and connected to said levers $M^2 M^2$ by links $M^3 M^3$, substantially as specified.
27. The combination with a sack filling mechanism, of an opening and closing sack holder for holding the sack open while being filled and closed while being sewed, a sack sewing device, and mechanism for closing said holder, said sack closing mechanism, a pair of oppositely moving sliding bars, levers $M^2 M^2$, levers $M^4 M^5$ pivoted together and connected to said levers $M^2 M^2$ by links $M^3 M^3$, substantially as specified.
28. The combination with a sack filling device, of a sewing device, a movable sack holder, a track or way for said holder, an intermittently moving up and down vibrating sack carrier G , mechanism for vibrating said carrier up and down, mechanism for driving said carrier, a clutch for throwing the carrier into gear with its driving mechanism, and a cam for operating said clutch automatically by raising said carrier to its limit, substantially as specified.
29. The combination with a sack filling device, of a sewing device, a movable sack holder or track or way for said holder, an intermittently moving up and down vibrating sack carrier G , mechanism for vibrating said carrier up and down, mechanism for driving said carrier, a clutch for throwing the carrier into gear with its driving mechanism, and a cam for operating said clutch automatically by raising said carrier to its limit, and second continuously moving sack carrier H , substantially as specified.
30. The combination with a sack filling device, of a sewing device, a movable sack holder or track or way for said holder, an intermittently moving up and down vibrating sack carrier G , mechanism for vibrating said carrier up and down, mechanism for driving said carrier, a clutch for throwing the carrier

into gear with its driving mechanism, and a cam for operating said clutch automatically by raising said carrier to its limit, second continuously moving sack carrier H, and spring 5 supports for said carrier H, substantially as specified.

31. The combination with a movable sack holder, of a track or way therefor, a sewing device, and a thread cutting device, substantially 10 as specified.

32. The combination with a movable sack holder, of a track or way therefor, a sewing device, and a thread cutting device and thread holding device, substantially as specified.

15 33. The combination with a movable sack holder, of a track or way therefor, a sewing device, and a spring actuated thread cutting device having an arm or projection projecting into the path of said holder, substantially as 20 specified.

25 34. The combination with a movable sack holder, of a track or way therefor, a sewing device, and a spring actuated thread holding and cutting device having an arm or projection projecting into the path of said holder, substantially as specified.

30 35. The combination with a sack filling and measuring device of a sack sewing device, a movable sack holder, and a slotted track or way for such holder extending from said filling device to said sewing device, substantially as specified.

35 36. The combination with a sack filling and measuring device of a sack sewing device, a movable sack holder, and a slotted track or way for such holder extending from said filling device to said sewing device, and means for moving said sack holder along said track or way, substantially as specified.

40 37. The combination with a sack filling and measuring device of a sack sewing device, a movable sack holder, and a slotted track or way for such holder extending from said filling device to said sewing device, and means for moving said sack holder along said track or way, the devices on said sack holder for engaging the mouth of the sack being movable to facilitate the release or discharge of the filled and sewed sack, substantially as specified.

45 38. The combination with a sack filling and measuring device of a sack sewing device, a movable sack holder, and a slotted track or way for such holder extending from said filling device to said sewing device, and means for moving said sack holder along said track or way, and a sack carrier, substantially as specified.

39. The combination with a sack filling and measuring device of a sack sewing device, a 60 movable sack holder, and a slotted track or way for such holder extending from said filling device to said sewing device, and means for moving said sack holder along said track or way, the devices on said sack holder for engaging the mouth of the sack being movable to facilitate the release or discharge of the filled and sewed sack, and a sack carrier, substantially as specified.

40. The combination with a sack filling and 70 measuring device of a sack sewing device, a series of movable sack holders, and a slotted track or way for such holders extending from said filling device to said sewing device, substantially as specified.

75 41. The combination with a sack filling and measuring device of a sack sewing device, a series of movable sack holders, and a slotted track or way for such holders extending from said filling device to said sewing device, and 80 means for moving said sack holders along said track or way, substantially as specified.

42. The combination with sack filling devices of a stationary sack sewing device, a movable sack holder, a track for said holder, 85 and an adjustable sack carrier to accommodate sacks of different sizes, substantially as specified.

43. A sack holder comprising opening and closing bars D' furnished with spring actuated rock shafts d' provided with hooks or pins d, substantially as specified.

44. A sack holder comprising opening and closing jaws D' furnished with spring actuated rock shafts d' provided with hooks or 95 pins d, and cams d² for operating said rock shafts by the opening of said bars D', substantially as specified.

45. The combination with a sack holder, of a track or way therefor, a sewing mechanism 100 and a device operated by the passage of the holder along said way for putting the sewing mechanism into and out of operation, substantially as specified.

46. The combination with a sack holder, of a track or way therefor, a sewing mechanism and a device operated by the passage of the holder along said way for putting the sewing mechanism into and out of operation, and a thread cutting device, substantially as specified.

ARTHUR T. TIMEWELL.
